UNITED STATES PATENT OFFICE.

NATHAN M. LOWER, OF SCHENECTADY, NEW YORK, ASSIGNOR TO LOCOMOTIVE STOKER COMPANY, OF PITTSBURGH, PENNSYLVANIA, A CORPORATION OF PENNSYLVANIA.

LOCOMOTIVE-STOKER.

1,368,273.

Specification of Letters Patent. Patented Feb. 15, 1921.

Application filed August 19, 1915. Serial No. 46,336.

To all whom it may concern:

Be it known that I, NATHAN M. LOWER, a citizen of the United States, and a resident of Schenectady, in the county of Schenectady and State of New York, have invented a new and useful Improvement in Locomotive-Stokers, of which the following is a specification.

This invention relates to fuel distributing mechanism, and particularly to mechanism for distributing fuel over the fire in a furnace fire box. While applicable to all types of furnaces, such as stationary installations, marine boiler furnaces or other power plants, the invention is more particularly designed for use in connection with stoker mechanism for railway locomotives, and for purposes of illustration has been so shown in the drawings.

One object of the invention is to provide improved mechanism for distributing the fuel in varying proportions over different parts of the fire box to produce a uniform combustion therein and secure an even fire and the production of the maximum number of heat units from the fuel. A further object of the invention is to provide fuel distributing mechanism which enables the fuel to be delivered at the sides and back of the fire as readily and effectively as in front of the firing opening, and which can be regulated while operating in order to vary the rate of feed of fuel to the different parts of the fire. A further object of the invention is to provide fuel distributing mechanism which can be utilized in connection with an automatic stoker for transferring the fuel from a source of supply to the fire box and introducing the same thereinto, and which is so arranged that the distribution of the fuel is controlled in accordance with the rate of transfer of the fuel from the source of supply to the fire box.

Further objects of the invention are in part obvious and in part will appear more in detail hereinafter.

In the accompanying drawings, Figure 1 is a longitudinal section through a fuel distributing device embodying the invention; Fig. 2 is a horizontal section, on a larger scale, on the line 2—2, Fig. 1; Fig. 3 is a cross section on the line 3—3, Fig. 2; Fig. 4 is a cross section on the line 4—4, Fig. 1; Fig. 5 is a cross sectional view on the line

5—5, Fig. 1; Fig. 6 is a sectional elevation, 55 showing a portion of one form of automatic locomotive stoker mechanism to which the invention may be applied; Fig. 7 is a sectional elevation thereof on the line 7—7, Fig. 6; Fig. 8 is a cross section, on a larger scale, 60 on the line 8—8, Fig. 7; Fig. 9 is a detail view, partly in elevation and partly in transverse section, showing the operating mechanism for a different type of automatic stoker mechanism; Fig. 10 is a longitudinal 65 section through the power cylinder therefor, illustrating the control of the fuel distributing device by the cylinder; and Fig. 11 is a diagrammatic view, illustrating the distribution of the fuel in the fire box. 70

In most of its features the fuel distributing device shown and described herein is identical with that shown and described in my prior application for locomotive stoker, filed October 16, 1912, Serial No. 726,108, 75 and this application is related to said prior application in so far as it claims subject matter common to the two cases and divided from said prior application.

As shown herein, the fuel distributing device comprises a hollow casing 1 which at one end communicates with an opening in the wall 3 of the fire box 4. The outer end of the casing 1 is closed by a detachable head 5, and said casing is also provided at its top with a fuel inlet 6 communicating with a source of supply of the fuel, as will more fully hereinafter appear, said inlet having a detachable cover or door 7 to enable fuel to be fed to the fuel distributing device by hand whenever desired, and to also give access to the interior parts for repairs or replacement if desired. In the casing 1 is slidably mounted a hollow piston, shown as embodying a head 8 provided with an inwardly extending scoop or shovel 8^a on which the fuel is delivered from the inlet 6, said head being attached to the inner end of a tubular member 9 which slides in the casing 1 between the inner surface thereof and the periphery of a circular guiding head 10 mounted on the inner end of a tube or pipe 11 attached at its outer end to the detachable head 5. The head 10 and the inner wall of the casing 1 are provided with packings 12 closely fitting the inner and outer surfaces of the tubular member 9, and said member at its outer end is provided with a

follower head 13 having an annular portion which enters an annular seat 14 on the inner face of the head 10 at the end of the piston stroke to cushion the piston against shock 5 at the end of its stroke.

The piston is operated by fluid pressure acting on its rear face and admitted through the bore of the tube 11, which communicates at its outer end with a hollow space in the 10 head 5 connected to a passage 15 in the wall of the casing 1. The inner end of tube 11 has a close bearing against the outer face of the head 8, so that pressure is confined against a limited area at the center of the 15 piston, to start the piston stroke, but as soon as the piston has moved forward slightly, the fluid pressure is admitted to a larger area on the outer face of the said piston, whereupon said piston is moved forwardly 20 with a sudden impulse to the end of its stroke, or until the follower head 13 reaches the cushioning space 14. The passage 15, the hollow space in the head 5, and the space within the tube 11 form in effect a reservoir 25 in immediate proximity to the piston or plunger, so that, as soon as the piston begins to move, the expansive power of the fluid pressure in this reservoir produces a very rapid movement of the piston. The 30 piston is returned preferably by spring pressure, such as by the tension of a spiral spring 16 attached at one end to the rear face of the piston head and at its other end to a nut 17 on a threaded bolt 18 having a 35 head lying outside of the detachable casing head 5. By adjusting the bolt 18 the nut 17 may be moved in or out to vary the tension of the piston retracting spring 16.

The sliding piston is also provided with 40 means for scattering or distributing the fuel thereon laterally in the furnace fire box. As shown, it is provided with two curved wings or vanes 20 provided with laterally extending arms 22 and pivoted on short vertical stub shafts 21 carried by the scoop or shovel 8^a. In the retracted position of the piston and shovel, as shown in Figs. 1 and 2, the wings or vanes 20 lie near the center line of the shovel, so that the fuel is delivered to 45 said shovel outside of the vanes. When the piston moves inwardly and is near the end of its stroke the arms 22 engage suitable abutments on the side walls of the casing 1, so that further inward movement of the piston 50 causes the vanes 20 to swing outwardly, as shown in dotted lines, Fig. 2, and thereby throw the fuel to one or both sides of the fire according to whether one or more vanes are provided. In the form shown the arms 55 22 travel in slots 23^a in side walls 8^b on the scoop or shovel 8^a, and the slots or grooves 23 in the side walls of the casing and engage shoulders 24 formed by the inner ends of said slots. On the rearward movement of 60 the piston the wings or vanes are returned 65

to initial position by engaging the inner end of the casing 1, and also by the engagement of the arms 22 with shoulders 24^a at the outer ends of the slots 23.

The fuel may be further distributed laterally by fluid pressure. For this purpose the central portion of the scoop or shovel 9 is provided with a fluid pressure conduit comprising a longitudinally extending hollow rib or boss 25, the bore or channel in which 70 communicates with a cross passage 26 at the inner end of the shovel. The outer end of the longitudinal passage is enlarged to provide a chamber 27 in which is located a sliding valve member 28 normally held against 75 a seat 29 by a compression spring 30. Said valve is smaller in diameter than the chamber 27 and is guided therein by outwardly extending wings 30^a. During the forward movement of the piston the pressure effective thereon is unable to unseat the valve 28 due to the pressure of the spiral spring 30, but when the piston reaches its inner limit of travel the pressure builds up and unseats 80 said valve, thus producing a rush of pressure through the hollow rib 25 and forming jets of fluid pressure at the open ends of the cross passage 26. These jets blow the fuel laterally in the fire box and assist in distributing the same. 95

As will be more fully hereinafter described, the fluid pressure for operating the piston may be so controlled as to produce light and heavy piston strokes, the light strokes for delivering the fuel near the front of the fire box and the heavy strokes for delivering it near the back. For example, referring to Fig. 11, the lines A, B, C and D illustrate the travel of the fuel on a heavy stroke, most of it falling near the back of the fire box, and the sudden action of the vanes throwing it well out toward the sides. The lines E, F, G and H illustrate the distribution on a light stroke of the piston, most of the fuel falling near the front of the fire box and not so far to its sides, due to the fact that the wings or vanes receive a lighter impulse and do not throw the fuel so far laterally. The fluid pressure for also distributing the fuel laterally may be made to operate either both on light or heavy strokes of the piston, or only on the light strokes, so that it offsets the decreasing force of the wings or vanes on light strokes and assists in distributing the fuel laterally during such strokes, but is not active on the heavy strokes when the wings or vanes act with full force. 110 115 120 125

If the spring 30 for seating the valve 28 is a comparatively heavy spring the fluid pressure acts on both light and heavy strokes of the piston, but the spring may be made lighter so that its tension is wholly overcome by the fluid pressure on a heavy stroke, which causes the valve 28 on such a stroke 130

to move the full length of the chamber 27 and seat and close against the inner end of said chamber. This causes the valve to first open and then almost immediately close 5 when the valve seats at the inner end of the chamber, so that substantially no fluid pressure issues from the cross passage 26 on heavy strokes. On light piston strokes, however, the valve 28 only moves part way 10 through the chamber 27 so that the pressure is fully effective in distributing the fuel laterally.

The strength of the piston stroke and the distribution of the fuel depend upon 15 the fluid pressure behind the piston head or the rate of supply of fluid pressure thereto. This is controlled by the valve mechanism shown in Fig. 5, comprising a hollow casing 32 which may be connected to or continuous 20 with the casing 1. In the casing 32 is a chamber 33 in which is slidably mounted a valve member having a stem 34 and two heads 35 each provided with a small through leak port 36. Pressure is supplied to the 25 chamber 33 between the heads 35 through a port or opening 37 from which it passes to the passage 15 through two ports or openings, marked 38 and 38^a respectively, communicating with passages leading to the passage 15. The port 38 is preferably smaller 30 than the port 38^a. The outer ends of the chamber 33 are closed by threaded plugs 39 having openings 40 therein, one of said 35 openings communicating with a pipe 41 and the other with a pipe 41^a. The sliding valve mechanism is normally held in central position by two compression springs 42 located between the plugs 39 and the outer ends of the piston heads 35, and the tension of 40 which springs may be adjusted by screwing the plugs 39 in or out as required.

Each head 35 acts as a valve to cover or uncover its port 38 or 38^a, and the outward movement of said heads may be controlled 45 by threaded stops 43 provided with graduated heads 44 coöperating with pointers 45 to indicate the position of said stops. By adjusting these stops the heads 35 will uncover the ports 38 and 38^a more or less and 50 thus enable the intensity of the different strokes of the piston to be varied.

When the valve stem 34 and heads move to the left in Fig. 5, the small port or opening 38 is uncovered, which allows pressure 55 to flow from the inlet 37 to the passage 15 and thence to the fuel injecting piston, but the fluid pressure supply is restricted so that only a light stroke is produced. When the valve head and stem move in the opposite 60 direction, or to the right, port 38^a is uncovered, which allows a more rapid supply of fluid pressure with a correspondingly heavy stroke.

The movement of the valve stem 34 and 65 heads 35 may be controlled or produced in

any suitable manner, but preferably by unbalancing the pressures on the outer faces of the two heads, either by diminishing the pressure effective on one head or by increasing that on the other. Fig. 8 shows one 70 arrangement of mechanism suitable for this purpose, said mechanism comprising a hollow casing 47 preferably open to the atmosphere through a port 47^a, and in which is located a rotary shaft 48 carrying a worm 49 75 connected to a worm wheel 50, the shaft 50^a of which is journaled in one side of the casing. One side of the casing is provided with an inwardly extending boss 51 contacting with one side face of the worm wheel 80 50 and provided with a through bore 51^a communicating with a pipe connected to the space on the outer face of one of the heads 35, and which may for example be the pipe 41^a. The other side of the casing 47 is 85 provided with a rotatably adjustable member 52 whose inner end contacts with the other face of the worm wheel 50, and which has a passage 52^a therethrough communicating with the space on the outside of the 90 other piston head 35, say through the conduit 41. The worm wheel 50 is provided with a through passage 53 arranged to register alternately with the passages 51^a and 52^a and thereby alternately open to exhaust 95 the chambers on the outer faces of the heads 35.

When passage 53 is out of registration with both of the passages 51^a and 52^a, communication to the chambers on the outer 100 faces of the heads 35 is closed except through the leak ports 36, so that pressure will build up in said chambers from the inlet 37. Each piston head is therefore subject to the pressure of a spring and to equal 105 pressures on its opposite faces, so that the valve mechanism shown in Fig. 5 lies in central or neutral position. Whenever the passage 53 in the worm wheel comes opposite one of the passages 51^a or 52^a the chamber 110 on the outside of the corresponding piston head is opened to exhaust, which allows the pressure on the inner face of said head to become effective and move over the valve, thus opening one or the other of the ports 115 38, 38^a to the source of pressure. As soon as the passage 53 moves away from its opening the pressure again builds up behind the head 35 and moves the valve mechanism 120 back to normal position. The fuel injecting 125 piston 8 then returns to normal position under the influence of the spring 16, the pressure behind said piston being exhausted through a passage 54 in one of the pistons 35, which communicates in normal position 125 of the valve mechanism with a channel in the casing leading to an exhaust opening 55.

The rotary member 52 is held against its face of the worm wheel 50 by a compression spring 56, which produces a tight seal be- 130

4
 tween said worm wheel at the open ends of the boss 51 and member 52 and prevents exhaust from the chambers of the controlling valve mechanism except when the opening 53 in the worm wheel is opposite the opening in one of said members. As shown in Fig. 8, the opening in the rotary member 52 is diametrically opposite the opening in the boss 51, so that successive strokes of the fuel 10 injecting piston are produced at uniform or regular intervals. Member 52, however, is provided with an operating handle 57 by means of which it may be turned around the axis of the worm wheel 50 so that the intervals between successive operations of the fuel injecting piston may be varied. By turning said member in the proper direction the time interval preceding a light piston stroke may be made shorter than that preceding a heavy stroke or vice versa. This 20 enables a larger quantity of fuel to be collected on the piston scoop before either the light or heavy stroke, so that a larger proportion of the fuel may be fed either to the 25 front or rear of the fire box.

The controlling device shown in Fig. 8 for the valve mechanism which operates the fuel injecting piston is operated by a rotary shaft 48, which may be any suitable shaft on the 30 locomotive. It may be hand-operated or operated by any suitable mechanism, but is especially adapted for connection to a locomotive stoker mechanism operated by a rotary engine. For example, Figs. 6 and 7 35 show locomotive stoker mechanism of the same form illustrated in my prior application referred to, said mechanism being operated by a rotary engine 60 which drives the rotary shaft 48 passing through the casting 47 of the controlling device. Said shaft is connected to a longitudinally extending spiral conveyer 61 which conveys the fuel from the locomotive tender (not shown) to a position beneath two upstanding conduits 45 63 through which the fuel is elevated to the fuel inlets 6 of the fuel injecting cylinders 1. The elevating mechanism comprises reciprocating bars provided with folding vanes, and is operated by a connection to the 50 shaft 48, in the same manner as in said prior application, and therefore requires no further description.

Fig. 9 is a view corresponding to Fig. 7 and showing a different form of locomotive 55 stoker mechanism. In this arrangement the fuel delivered by the longitudinal conveyer extending from the locomotive tender to the engine is elevated to the fuel injecting devices by two spiral conveyers 66 provided 60 with pinions 67 at their lower ends, both of which are operated by a reciprocating rack 68 connected to a piston rod 69, the piston 70 of which is reciprocated back and forth in a cylinder 71 in the usual manner, by alternately admitting fluid pressure to opposite

ends of said cylinder and exhausting it therefrom, through ports 70^a and 70^b at the ends of said cylinder. This cylinder is provided intermediate its ends with two side ports or openings, marked 72 and 73 respectively, port 72 being connected by a suitable conduit, such as the conduit 41, Fig. 5, with the chamber behind one head 35 of the controlling valve mechanism, the other port or opening 73 being similarly connected by the 75 conduit 41^a with the chamber behind the other head.

The controlling valve mechanism of Fig. 5, in this case, is operated by increasing the pressure behind one of said piston heads in 80 contradistinction to decreasing or exhausting it, as in the form before described. Assuming the piston 70 is at one end of its stroke, say at the extreme left in Fig. 10, both heads 35 of the valve mechanism are 85 subject on their outer faces to the same pressure, that is, to atmospheric pressure, because the space to the right of the piston 70 is open to exhaust. Pressure is admitted on the left-hand side of the piston 70 which 90 forces it to the right. When the piston passes the port 72 a full supply of fluid pressure flows through the port 72 and conduit 41 and becomes effective on the outer face of the left-hand head 35 of the valve 95 mechanism, consequently moving said valve mechanism to the right in Fig. 5 and opening the port 38^a to the pressure supply 37, which produces a heavy stroke of the fuel injecting piston. As soon as the piston has 100 passed the port 73 pressure is also admitted to the chamber on the outside of the right-hand piston 35 in Fig. 5, so that the pressures on the two heads 35 are equalized. Consequently, the valve mechanism returns 105 to neutral or central position and the fuel injecting piston is retracted by its spring 16. When the piston moves to the left in Fig. 10 pressure is first admitted through the port 73 to the space behind the right-hand head 35, which moves the valve mechanism to the 110 left in Fig. 5 and opens the port 38 to the pressure supply port 37, so that a light stroke of the fuel injecting piston is produced. When the piston in its travel to the 115 left also uncovers the port 72 pressure is also supplied to the space behind the left-hand head 35 and the valve mechanism can move to neutral position to allow the fuel injecting piston to return.

The fuel distributing mechanism described has the advantage of enabling a very accurate distribution of the fuel in accordance with the demands of the fire box, and especially the demands of different portions of the fire bed therein. It enables the fuel to be distributed very evenly over the entire fire box or larger proportions of fuel to be placed on different portions of the fire 125 therein. All adjustments to vary the supply 130

of the fuel to different parts of the fire box can be made while the entire mechanism is operating, so that the fireman can watch carefully the progress of the fire and make whatever adjustment is necessary to keep a uniform fire over the entire area of the fire box. The fuel injecting pistons may be made to operate with strokes of varying intensity so as to throw a part of the fuel clear to the inner end of the fire box and deliver a part in the front portion near the fire door. The laterally movable vanes or wings and the lateral jets of fluid pressure also enable the fuel to be thrown to the extreme sides of the fire box, so that all of the fuel is not packed or arched in the center with liability of caking, crusting or coking.

What I claim is:—

1. Fuel injecting mechanism for automatic stokers, comprising a cylinder, a fuel-injecting plunger therein, automatic means for regulating the intensity of the plunger strokes, and means for varying the relative time interval between the strokes of different intensity.

2. Fuel injecting mechanism for automatic stokers, comprising a cylinder, a fluid pressure advanced fuel-injecting plunger therein, automatically acting valve mechanism for varying the supply of fluid pressure to said cylinder to regulate the intensity of the plunger strokes, and means for regulating the relative time interval between the strokes of varying intensity.

3. Fuel injecting mechanism for automatic stokers, comprising a cylinder, a fluid pressure advanced fuel-injecting plunger therein, automatic means for supplying different degrees of pressure to said cylinder to vary the effect of the alternate plunger strokes, and means for regulating the relative time interval between the alternate plunger strokes.

4. Fuel injecting mechanism for automatic stokers, comprising a cylinder, a fuel-injecting plunger therein, means for supplying motive fluid to said cylinder for operating the plunger, automatically acting valve mechanism for controlling the fluid pressure supply to vary the intensity of the alternate strokes of the piston, and means for varying the relative time interval between the alternate strokes.

5. Fuel injecting mechanism for automatic stokers, comprising a cylinder, a fuel-injecting plunger therein, means for supplying motive fluid to said cylinder to operate the plunger in one direction, yielding means for moving said plunger in the opposite direction, automatically acting valve mechanism for controlling the supply of motive fluid to the cylinder so as to cause the alternate forward movements of the plunger to vary in intensity, and means for varying

the relative time interval between the alternate forward strokes of the plunger.

6. Fuel injecting mechanism for automatic stokers, comprising a cylinder, a fluid pressure advanced fuel-injecting plunger therein, automatically acting valve mechanism for controlling the supply of motive fluid to the plunger to cause the alternate strokes of the plunger to vary in intensity, and means for controlling the valve mechanism for varying the relative time interval between the alternate strokes of the plunger.

7. Fuel injecting mechanism for automatic stokers, comprising a cylinder, a fluid pressure advanced fuel-injecting plunger therein, a fluid pressure operated valve mechanism for controlling the supply of motive fluid to said plunger so as to produce alternate strokes of varying intensity, and means for controlling the supply of motive fluid to said valve mechanism and arranged to vary the relative time interval between the strokes of varying intensity.

8. In a stoker, in combination, a fluid pressure advanced fuel injecting plunger, a valve for controlling the application of pressure to the plunger, and means for automatically shifting the valve to apply such pressure alternately at higher and lower intensity and at alternately longer and shorter intervals.

9. In a stoker, in combination, a fluid pressure advanced fuel injecting plunger, a valve for controlling the application of pressure to the plunger, and automatic means for shifting the valve at alternately longer and shorter intervals.

10. In a stoker, in combination, a fluid-pressure advanced fuel injecting plunger, a fluid-actuated valve controlling the application of pressure to the plunger, and means for applying shifting pressure to the valve at alternately longer and shorter intervals.

11. In a stoker, in combination, a fluid-pressure advanced fuel injecting plunger, a fluid-actuated valve controlling the application of pressure to the plunger and arranged to admit such pressure at varying degrees of intensity, and a rotative valve for admitting pressure to actuate the controlling valve and arranged to shift such valve to admit pressure to the plunger at alternately higher and lower intensity.

12. In a stoker, in combination, a fluid-pressure advanced fuel injecting plunger, a fluid-actuated valve for controlling the application of pressure to the plunger, a rotative valve for admitting actuating pressure to the controlling valve, and means for varying the action of the rotative valve to open at alternately longer and shorter intervals.

13. In a stoker, in combination, a fluid-pressure advanced fuel injecting plunger,

two differential ports for admitting pressure to the plunger, valve mechanism controlling such ports, and means for shifting the valve mechanism to open such ports alternately and at alternately longer and shorter intervals.

14. In a stoker, in combination, a fluid-pressure advanced fuel injecting plunger, two differential ports for admitting pressure to the plunger, valve mechanism controlling such ports, and a rotative valve controlling fluid-pressure for shifting the valve mechanism to open such ports alternately.

15. In a stoker, in combination, a fluid-pressure advanced fuel injecting plunger, two differential ports for admitting pressure to the plunger, valve mechanism controlling such ports, and a rotative valve controlling fluid-pressure for shifting the valve mechanism to open such ports alternately and at alternately longer and shorter intervals.

16. In a stoker, in combination, a fluid-pressure advanced fuel injecting plunger, a valve casing having differential ports for admitting pressure to the plunger, a balanced valve movable in opposite directions to open such ports respectively, and means for unbalancing the valve and arranged to shift said valve alternately in opposite directions.

17. In a stoker, in combination, a fluid-pressure advanced fuel injecting plunger, a valve casing having differential ports for admitting pressure to the plunger, a balanced valve movable in opposite directions to open such ports respectively, and means for unbalancing the valve and arranged to shift said valve alternately in opposite directions and at alternately longer and shorter intervals.

18. In a stoker, in combination, a fluid-pressure advanced fuel injecting plunger, a valve casing, differential ports for admitting pressure to the plunger, a valve having an induction cavity intermediate its ends and arranged to register with such ports in

alternation by movements in opposite directions, pressure chambers at each end of the valve, and a rotary valve for varying the pressure in such chambers alternately.

50

19. In a stoker, in combination, a fluid-pressure advanced fuel injecting plunger, a valve casing, differential ports for admitting pressure to the plunger, a valve having an induction cavity intermediate its ends and arranged to register with such ports in alternation by movements in opposite directions, pressure chambers at each end of the valve, and a rotary valve for varying the pressure in such chambers alternately and at alternately longer and shorter intervals.

55

20. In a stoker, in combination, a fluid-pressure advanced fuel injecting plunger, two differential ports for admitting pressure to the plunger, valve mechanism controlling such ports, means for adjustably varying the range of movement of the valve mechanism, and means for shifting the valve mechanism to open such ports alternately.

60

21. In a stoker mechanism, in combination, a fuel injecting means operating intermittently with varying intensity, mechanism for feeding fuel to said means, and mechanism for varying the periods between the successive actions of said injecting means independently of the rate of fuel supply.

65

22. In a stoker mechanism, in combination, an oscillatory fuel injecting vane, mechanism for supplying fuel in position to be injected by said vane, and mechanism for actuating said vane to inject the fuel with an intensity independent of the rate of supply of fuel to said vane.

70

In testimony whereof, I have hereunto set my hand.
